UNITED STATES PATENT OFFICE

CARL A. SCHMIDT, OF WATERLOO, AND JAMES WESTERGAARD, OF REINBECK, IOWA

COMBINATION LOCKING MEANS FOR RESERVOIR BUNGS AND FAUCETS

Application filed March 7, 1928. Serial No. 259,896.

Our invention relates to improvements in locking devices, and the object of our improvements is to supply combination locking means for reservoir or barrel bungs and their 5 taps or faucets, and so constructed as to be readily mounted thereon and quickly removed from either when desired, with independent locking devices for the bungs and faucets, whereby unauthorized filling or draining of 10 a container are prevented.

This object we have accomplished by the means which are hereinafter described and claimed, and which are illustrated in the accompanying drawings, in which Fig. 1 is 15 a diametrical vertical section of a barrel-head and of the bung locking means applied thereto, and in which a faucet thereon and other elements are shown in side elevation, parts being broken away. Fig. 2 is a fragmentary 20 end elevation of the barrel-head showing our improved locking devices mounted thereon, a part of the bung locking casing being broken away.

Our invention is not restricted to the precise construction and arrangement of parts herein shown and described, nor to the various details thereof, as the same may be modified or rearranged in various particulars 25 without departing from the spirit and scope 30 of our invention, one practical embodiment of which has been herein illustrated and described without attempting to show all of the various forms and modifications in which our invention might be embodied.

Our invention is applicable to any species 35 of container. We show at 1 a barrel having a head 2, and as positioned on its side. In the vertical diameter of the head 2 are a bung-hole above and a tap-hole below, both near the 40 rim. In the bung-hole is fitted an interiorly threaded sleeve 3 to receive the threaded stem of a metal bung 4 removably. The bung has a terminal outer expansion whose peripheral 45 shape is immaterial as shown at 5 and slightly spaced away from the head. The numeral 10 denotes a flat ring mounted concentrically around the bung 4 behind the expansion rim 5 thereof and abutting the barrel head 2. The lower part of said ring has a projection 11 50 extending at a right angle outwardly from

the head and having a terminal aperture 12. At the opposite part of the ring 10 a portion 6 is pressed outwardly to provide a seat between it and the head 2 for an inturned lip 7 projecting from the rear marginal edge of a 55 concave or cupped casing member 8 which incloses the bung and ring outside the head 2. The casing 8 has an oblong slot 9 traversed by the ring projection 11 so that the aperture 12 of the latter is without but close to the 60 head of the casing.

Directly below the bung-hole is positioned the tap-hole in which is mounted an interiorly threaded sleeve 21 to receive removably the threaded stem 22 of a faucet 23 which is of 65 the valvular type having an operating arm 25 pivoted at 24 thereon to actuate the inner valve not shown. This arm is channeled longitudinally and has a longitudinal slot 26 near its free end to receive a staple 27 there- 70 through which is fixed on the faucet spout.

The numeral 17 denotes a chain connector positioned in a direct line between the projection 11 and the staple 27, or approximately so, and having at the top an elongated hook 75 13 linked to the chain by a welded eye 14. The free terminal 15 of the hook is preferably longer than the other side part of the hook. The hook 13 is adapted to enter the aperture 12 of the projection 11, while a long terminal 80 link 20 of the chain is passed over the staple 27. The padlock hasp at 29 is linked into the staple 27 outside of the link 20. Another padlock 16 has its hasp passed around the hook 13.

In the application of the locking means 85 shown, both the bung 4 and the operating arm 25 of the faucet 23 are locked, so that the former cannot be removed for unauthorized re-filling of the container by anyone other than the concern supplying the container to 90 the user, nor can be faucet arm be unlocked, which prevents thefts by way of the faucet of the contents of the container. The chain connector is disposed in a direct line from the bung to the faucet with little or no slackness. 95 The concern supplying the container to a user may have its individual lock 16, so that the user cannot permit the re-filling of the container by a competitor.

The flexibility of the chain connector al- 100

lows it to be used to connect a bung on a barrel or tank top with a faucet or other tap on the side thereof by conforming around the intermediate angle of the container, and in 5 the most direct line therebetween, which could not be done with a rigid connector.

Having described our invention, what we claim as new and desire to secure by Letters Patent, is:

10 1. Locking means of the character described, comprising in combination with a rimmed bung removably secured in and closing the bung-hole of a container and with a tap also mounted on the container and provided with a valve and valve-operating means, an apertured device rotatably interlocked with the bung rim, a chain connector having a long terminal hook and a long end link adapted to be releasably engaged respectively with said apertured device and with the valve-operating means of the tap to fasten them both in their closed positions, and locking-devices removably interlocked respectively with said terminal hook and end link, 25 independently to prevent the removal of said devices from the bung and tap.

2. Locking means of the character described, comprising in combination with a bung having rimmed engaging-means and removably secured in and closing the bung-hole of a container, and with a tap having a valve and a valve-operating device and also mounted removably in a tap-hole of the container, of a connector between said bung and the said tap, comprising a chain having a relatively long end hook, a ring surrounding said bung and engaged between its engaging-means and the container and having a peripheral and terminally apertured projection, a concave 40 casing having an edge tongue bent inwardly and engaged between said ring and the container and having a single aperture traversed by said projection whose aperture is positioned outside of the casing, said tap having 45 a fixed staple thereon and said valve-operating device including a pivoted arm apertured to be traversed by said staple when the valve is in closed position, the hook of said connector being interlinked with the apertured 50 terminal of said projection and an end link being engaged with said staple outside of said arm, a padlock having its hasp releasably interlocked with said staple, and another padlock having its hasp inclosing and locking together the opposite parts of the hook which 55 is engaged with said apertured projection.

In testimony whereof we affix our signatures.

CARL A. SCHMIDT.

60 JAMES WESTERGAARD.
